OXYGEN ADMINISTERING MASK UNIT

Dudley H. Grimm, Leawood, Kans., assignor to Puritan Compressed Gas Corporation, Kansas City, Mo., a corporation of Missouri

Filed July 16, 1962, Ser. No. 70,935

Term of patent 14 years

(Cl. D83—1)

FIG. 1 is a front elevational view of an oxygen administering mask unit, showing my new design with the tube member broken away in part to indicate indeterminate length;

FIG. 2 is a side elevational view thereof with the tube fragmentarily shown for convenience of illustration;

FIG. 3 is a rear elevational view thereof as shown in FIG. 2;

FIG. 4 is a top plan view of an oxygen administering mask unit; and

FIG. 5 is a longitudinal sectional view taken substantially along line 5—5 of the mask member shown in FIG. 1.

The fragmentary bag member shown in broken lines in FIGS. 1, 2 and 3 is for illustrative purposes only.

I claim:

The ornamental design for an oxygen administering mask unit, as shown and described.
